2,599,025

METHOD OF WORKING THE INNER SURFACE OF A HOLLOW BODY

Jacob J. Stampen, Hollywood, Ill., assignor to Babson Bros. Co., a corporation of Illinois.

Application December 3, 1948, Serial No. 63,382

7 Claims. (Cl. 51—290)

1

This invention relates to an apparatus for working the inner surface of a hollow body having a relatively small opening in one wall thereof, and relates particularly to an apparatus for working the inner surface of the circumferential weld of a milker pail having a relatively small opening in one wall offset from the transverse axis of the pail.

Suspended milkers, of the type shown in McCornack Patent 1,859,213, employ a pail of substantial diameter with a lid opening of less than one-half such diameter and with a height of the same order. For example, a commercial suspended milker now being sold on the market uses a pail with a diameter of 15½ inches, a maximum height of 7½ inches and an opening in the top portion with a diameter in the neighborhood of about 7 inches. This opening is positioned adjacent one edge of the top portion. While the pail is being used, this opening is closed by a lid sealed vacuumtight to the pail with the lid having connector nipples for the milker inflations and also carrying the pulsator and its connections. The general construction and operation of a milker of this type are well known and need not be described further.

Milker pails of the above type that have heretofore been made have involved the use of an overlapped seam or a butt-welded juncture between upper and lower sections of the pail, which extends circumferentially around the finished pail and divides the pail into two approximately equal halves, a butt-welded juncture being preferred so as to avoid internal pockets that are difficult and often impossible to clean. In manufacturing the milker pail there is normally formed an upper part made in one draw or series of draws, in at least one forming operation, and a lower part separately drawn or formed.

After the butt weld joining the upper and lower parts had been formed it was found difficult to smooth the inner surface of the weld because of the small opening into the pail and because this opening is off center and adjacent to one edge of the top portion of the pail. Even under the best conditions of hand finishing this weld would be rough and offer pockets for the collection of bacteria. I have devised a new apparatus for working the inner surface of the circumferential weld so that it can be smoothed down and given all the advantageous characteristics of a truly seamless pail even from the inner surface thereof. A pail finished with the apparatus of this invention has a completely smooth inner wall which not only has the desirable smooth

appearance, but which completely avoids unwashable pockets being formed on the inner surface of the weld. Grinding and polishing of the outer surface is, of course, easily accomplished by conventional machinery.

Other features and advantages of my invention will be apparent from the following specification, and the drawings, in which:

Fig. 1 is a fragmentary side elevation, partially in section, of one embodiment of the apparatus used for rough grinding the inner surface of the circumferential weld of a milker pail, said milker pail being shown in dotted lines.

Fig. 2 is a fragmentary end elevation of the apparatus of Fig. 1 taken from the righthand side thereof.

Fig. 3 is a transverse section taken through the apparatus substantially along line 3—3 of Fig. 4, with the milker pail being shown in solid lines.

Fig. 4 is a transverse section taken substantially along line 4—4 of Fig. 2, with the milker pail being shown in solid lines.

Fig. 5 is a section taken substantially along line 5—5 of Fig. 1.

Fig. 6 is a fragmentary side elevation of one embodiment of the apparatus used in polishing the internal surface of the pail weld after the grinding operation, said pail being shown in dotted lines.

Fig. 7 is a section taken along line 7—7 of Fig. 6 and partially broken away for clarity of illustration, with the milker pail being shown in solid lines.

Fig. 8 is a section taken substantially along line 8—8 of Fig. 7.

Fig. 9 is a section taken substantially along line 9—9 of Fig. 7.

The essential features of my invention are the provision of an apparatus comprising a rotatable driven shaft, driving means operatively connected thereto and means mounted on the shaft for operation against the inner surface of the pail in the region of the circumferential weld upon rotation of the shaft. The operating means is dimensioned so that the opening in the pail can be slipped thereover with the operating means being within the pail during the operation thereof. Although the apparatus is primarily intended for treating the inner surface of a milker pail adjacent the circumferential weld, it is believed obvious that it can be employed for treating the surface of any hollow body, particularly one having a relatively small opening in one wall thereof, and especially any hollow body having such an opening in one wall adjacent one edge of the

2

body and offset from the transverse axis of the body.

In working the inner surface of a hollow body such as a milker pail two operations are preferably used. In one operation the rough weld is ground with an abrasive, while in the second operation this ground weld is polished to provide a smooth continuous surface on the inside of the body or milker pail adjacent the weld. General features of both forms of apparatus are the same, however, as in both forms there is preferably provided a rotatable driving shaft, a rotatable driven shaft spaced therefrom, driving means interconnecting these shafts and means mounted on the driven shaft and including a working member for operation against the inner surface of the body or pail upon rotation of the shafts. The driven shaft, interconnecting driving means and operating means are dimensioned so that the opening in the hollow body can be slipped thereover with the driven shaft and operating means being within the body and the driving shaft extending through the opening. When the body acted upon is the milker pail having a substantially circular circumference, the driven shaft is located at substantially the transverse axis of the pail.

In the accompanying drawings, Figs. 1 to 5 illustrate one embodiment of the apparatus used in the first operation in which the rough weld is ground down. Figs. 6 to 9 illustrate one embodiment of the apparatus in which the ground weld is polished so as to present a smooth appearance.

In the grinding apparatus of Figs. 1 to 5, there is provided a base member 10 upon which the apparatus is mounted. Extending upwardly from this base member is a bearing support 11 having mounted on the upper end thereof an extended bearing 12 through which extends a rotatable driving shaft 13. The outer end of this driving shaft has attached thereto a driving means, here illustrated as a belt pulley 14 having attached thereto a pair of driving belts 15. These belts may be attached in driving relationship to an electric motor or other source of power.

The end of the bearing 12 opposite the belt pulley 14 extends to the end of the driving shaft 13 as shown in Fig. 4. Located on this end of the bearing 12 is an upwardly extending mounting means or rigid housing 16. Located within this housing is a first circular gear 17 mounted on the end of the driving shaft 13 for rotation therewith, a second circular gear 18 meshing with the first gear 17 and mounted for rotation on a short shaft 19 wholly within the housing 16 and a third circular gear 20 meshing with the second gear 18 and located adjacent the upper end of the housing 16. This third circular gear 20 is fixedly mounted on a driven shaft 21 positioned in the upper end of the housing 16 and extending therefrom. With this arrangement the driven shaft 21 is rotated by rotation of the driving shaft 13. In order to aid in assembling the various gears within the housing 16, this housing is preferably made in two parts with the gears located therebetween and with these parts fastened together by rods, pins, bolts or the like 22.

Attached to the outer end of the driven shaft 21 for rotation therewith are means for operating against the inner surface of the milker on rotation of shafts 13 and 21. In the embodiment shown in Figs. 1 to 5 this operating means includes a pair of substantially parallel arms 23

mounted substantially centrally on an annular member 24 that is attached to the driven shaft 21. Each arm 23 is held in place by means of a pin 25 extending from the annular member 24 through an arm 23.

On each end of the pair of arms 23 there is provided a holder 26 forming a socket that is closed at the sides and the inner end but open at the outer end. Each holder 26 is adapted to hold working member, here shown as a grinding member 27 with this grinding member being fitted loosely in the holder and extending therebeyond. The sides 26a of the holder 26 are attached at the inner end thereof to a block 28 with this block forming the inner end of the holder and being attached to a bar 29. The holder 26 is slidably held between the arms 23 and the ends of the bar 29 are attached to ends of coil springs 30. The other end of each spring 30 is attached to an arm 23 near the outer extremity thereof. With this arrangement each bar 29 and thus the holder 26 are urged outwardly by the tension of the coil springs 30 so that the grinding members 27 are urged against the inner surface of the milker pail 31 in the areas adjacent the circumferential weld 31a. As can be seen, particularly in Figs. 3 and 4, the arms 23 have lengths substantially less than the diameter of the pail 31 and the outer ends of the holders 26 are normally spaced inwardly substantial distances from the inner surface of the pail.

In the preferred method of making the weld 31a, the contacting edges of the metal are heated and pressure is applied to fuse the softened metal together. Thus no added welding metal is applied. In the drawings the weld 31a is indicated as a line for purposes of illustration only as in the finished construction there is no observable seam.

In order to hold the pail 31 in position, there are provided means embracing the pail around the periphery thereof in the region opposite the path of travel of the grinding members and adjacent the weld 31a. In the embodiment shown this embracing means comprises a pair of substantially semi-circular metal bars 32 and 33. Each bar is relatively heavy and when in closed position have their ends substantially abutting each other on a diameter of the milker pail 31. The lower metal bar 32 is preferably made solid while the upper metal bar 33 is preferably provided with a series of openings 33a extending transversely therethrough. As the bars 32 and 33 are preferably made of steel, they serve to conduct heat away from the pail 31. This heat which is developed by the friction of the grinding members 27 against the inner surface of the pail is often considerable and the provision of means for conducting this heat away from the pail is an important feature of this invention as it avoids possible damage to the metal of the pail caused by overheating thereof in the region of the weld 31a. The openings 33a in the upper metal bar 33 aid in dissipating the heat in this part to the surrounding area.

The metal bars 32 and 33 are hingedly attached together at one of their adjacent ends by means of a pair of metal hinge straps 34. These hinge straps are located on opposite sides of the bars 32 and 33 and are attached to the bars by means of pins 35. The opposite ends of the bars 32 and 33 are removably held together by means of a latch 36 rotatably mounted on the lower bar 32 and engaging studs 37 on the upper bar

33. The latch may be any form desired but, as shown, comprises a yoke structure having a central portion 36a spaced from the lower bar 32 and a pair of legs 36b extending from opposite sides of this central portion and located on opposite sides of the upper and lower bars 32 and 33. The outer ends of these legs are provided with notches which engage the studs 37 and the central portion 36a is provided with a downwardly extending lever 38 for operating the latch 36.

The lower metal bar 32 rests on the base member 10 and the upper metal bar 33 is provided with a handle 39 near the end of the bar that is adjacent the latch 36. This handle is used to raise the upper bar 33 from the pail 31 and lower the bar on to the pail. When the upper bar 33 is in open position, as shown by dotted lines in Fig. 2, it rests against a bracket 40 attached to the lower metal bar 32 adjacent the hinge straps 34.

In order to locate properly the milker pail 31 with relationship to the grinding members 31, there is provided means bearing against the pail on the side opposite the opening 31b. In the embodiment shown in Figs. 1 to 5, this means comprises a locating member 41 in the form of an annular metal plate having the lower portion 41a extending downwardly and to the left, as viewed in Fig. 2. The bottom end of this lower portion 41a has attached thereto a collar 41b rotatably mounted on a shaft 42, which is attached to the base member 10. This collar 41b is held between a mounting member 43 in which the shaft 42 is held and an annular collar 44 fixedly mounted adjacent the outer end of the shaft 42. The mounting member 43 and annular collar 44 permit movement of the locating member 41 in a plane which is substantially parallel to the upper and lower metal bars 32 and 33. In order to operate the locating member 41, there is provided an outwardly extending handle 45 attached to the locating member adjacent the top thereof.

Although the apparatus of Figs. 1 to 5 is primarily intended for grinding down the inner surface of the weld, it is believed obvious that with minor modifications this same apparatus could be used for any working operation such as the final polishing operation. The principal changes would, of course, be to provide a polishing member in place of the grinding member 27. In actual practice, however, in order to increase production, it is preferred that a separate mechanism be employed for the polishing operation. The polishing apparatus is constructed generally similar to the apparatus used for grinding. The principal difference between the grinding apparatus and polishing apparatus is that in the polishing apparatus, as illustrated, only one polishing member is employed and a different type of embracing means is used for holding the milker pail in place during the polishing operation. In the polishing apparatus there is no need to provide the heat conducting bars as the heat generated during the polishing operation is much less than that generated during the grinding operation. Also means are provided in the polishing apparatus for reciprocating the milker pail laterally of the plane of rotation of the operating means which does the polishing during the rotation thereof. This reciprocating means is employed so that the polished area will blend smoothly into the interior surface on either side of the polished area.

In the drawings, Figs. 6 to 9 illustrate one em-

bodiment of the polishing apparatus. In this embodiment there is provided a base member 46, a bearing support 47 at one end thereof, an extended bearing 48 held by the bearing support 47 and a driving shaft 49 within the extended bearing 48. The outer end of the driving shaft has attached thereto a belt pulley 50 which is driven by a pair of driving belts 51. These belts may be driven by an electric motor or other source of power.

The inner end of the extended bearing that is opposite the pulley 50 has attached thereto a mounting means, here shown as a rigid housing 52. The driving shaft 49 extends into the rigid housing 52 and has mounted on the end thereof a driving means, here shown as a first circular gear 53 mounted on the end of the shaft 49, and a second circular gear 54 in engagement with the first gear. The second gear 54 is mounted on a driven shaft 55 so that rotation of the gears causes rotation of the driven shaft. This driven shaft 55 extends beyond the housing 52 on the side opposite the driving shaft 49. The outer end of the driven shaft has attached thereto an operating means, here shown as including an arm 56, mounted for rotation with the driven shaft 55 and carrying on the end thereof a working member, here shown as a polishing member 57.

30 The polishing member 57 is mounted on a pair of substantially parallel rods 58 which are slidably held in the outer end of the arm 56. Each rod 58 is held in a longitudinal substantially circular cavity 56a opening at the end of the arm 56. Located in each cavity 56a is a compression spring 59 operating against the inner end of its rods 58 to urge the polishing member 57 outwardly against the inner surface of the milker pail 31 in the area adjacent the weld 31a. Adjacent the inner end of each rod 58 there is located a set screw 60 movable in a longitudinal slot 56b in the arm 56. With these set screws 60 the pressure of the polishing member against the milker may be regulated to either a maximum or minimum value. When the set screws 60 are loosened so that they do not engage the sides of the slots 56b, the force developed will be the centrifugal force of the polishing member 57 and associated structure.

45 In order to balance the arm 56, there is provided a counterweight 56c formed as a part of the arm. This counterweight extends beyond the driven shaft 55 on the end of the arm opposite the polishing member 57.

50 In order to hold the milker pail 31 in position during the polishing operation there is provided an embracing means for the pail. This embracing means serves as a locating means for the pail and engages the milker pail around the periphery thereof in the region opposite the path of travel of the polishing member and also on the side of the pail opposite the opening 31b. In the embodiment shown, this embracing or locating means comprises a pair of grasping members 61 and 62. These grasping members, which may be constructed of blocks of wood, have hollowed out sections 61a and 62a each substantially semi-circular in contour so that they will grasp and hold the outer circumferential surface of the pail when the members 61 and 62 are arranged together, as shown in Fig. 7. Both grasping members 61 and 62 are of substantially rectangular shape and the upper member 62 is hingedly mounted at one edge thereof on a corresponding edge of the lower member 61 by means of

the hinge structure 63. Because of the hinge 63, the upper grasping member 62 may be moved to open position as illustrated by dotted lines in Fig. 7. The two members 61 and 62 are locked together by means of a quickly releasable lock 5 64 of conventional design.

During the polishing operation it is customary to employ a polishing oil or the like in order that a smooth finish may be more easily achieved. As the milker pail 31 is positioned so that the opening 31b is on the bottom thereof during the polishing operation, it has been found necessary to turn the pail so that oil will be less likely to spill out during the polishing operation. In the embodiment of the invention shown in the drawings, this is accomplished by arranging the bottom of the lower grasping member 61 at an acute angle to the horizontal, as shown in Fig. 4. In this arrangement the driving shaft 49 and the bearing 48 are located adjacent the top of the pail opening 31a and a line connecting the driving shaft 49 and the driven shaft 55, and at a right angle to at least the driven shaft, is at an acute angle to the horizontal.

The lower grasping member 61 has attached thereto a pair of extended collars 65 in the form of circular pipes. Each collar 65 is at a lower corner of the lower grasping member 61 and are arranged substantially parallel to each other and at right angles to the plane of the grasping member. Each collar is supported on a substantially circular bar 66 with these bars being arranged substantially parallel to each other. These bars 66 have their ends attached to mounting members 67 which are supported on the base member 46. As can be seen from Figs. 6 and 7, the rear bar 66 is at a higher level than the front bar.

The provision of the collars 65 and circular bars 66 permits reciprocation of the grasping member 61 and 62 and thus the milker pail 31 during the polishing operation. Such reciprocation results in a blending of the polished area with the surfaces on either side thereof so as to give a smooth appearance to the inner surface of the milker pail.

In the embodiment shown, the reciprocation of the milker pail is obtained by providing a metal strap 68 rotatably attached to the bottom surface of the lower grasping member 61 with this strap being rotatably fastened to the end of a lever 69, which is mounted for rotation about a fulcrum 69a. The lever 69 is provided with a handle portion 69b so that the lever may be moved back and forth and thus reciprocate the grasping member and the pail during the polishing operation.

The polishing member 57 may have any form desired. In the embodiment shown, the member comprises a trough-like holder 57a having a felt body 57b extending therefrom with this felt body being surrounded with a cloth layer 57c. The actual polishing element that is used is a strip of emery cloth 57d on the outermost surface of the cloth layer 57c. Means are preferably provided for removing the emery cloth whenever it becomes worn and replacing it with a new one.

In the working or finishing of the weld 31a, the weld is first ground down by means of the apparatus shown in Figs. 1 to 5 and then polished in the apparatus shown in Figs. 6 to 9. In the operation of the apparatus of Figs. 1 to 5 the upper metal bar 33 is turned to its open position, as illustrated in dotted lines in Figs. 5 and 6, and

the milker pail is then slipped over the holders 26, arms 23 and gear housing 16 and moved to the position shown in Fig. 4. The grinding members 27 may then be placed within their holders 26 by moving the holders inwardly against the action of the springs 30 until there is room for inserting the grinding members within the holders. The locating member 41 is then rotated into position as shown in Fig. 1, and the bottom of the milker pail pressed against this member. The upper metal bar 33 is then moved into position by means of the handle 39 and the upper and lower members 32 and 33 locked together by means of the latch 36. Power is applied through the pulley 14 to rotate the driving shaft 13 and thus the driven shaft 21. The arms 23 are rotated at the desired rate of speed and the grinding members 47 are forced against the weld 31 by a combination of spring and centrifugal forces acting on these grinding members. Heat generated in the area of the pail adjacent the weld 31a is conducted away from the pail by the metal bars 32 and 33. After the weld has been ground down the desired distance, the rotation of the apparatus is stopped, the upper metal bar released by opening the latch 36 and this bar turned around its hinge to the position shown in the dotted lines in Fig. 2. The milker pail is then removed from the apparatus.

In the polishing operation the upper grasping member 62 is turned to the position shown in the dotted lines in Fig. 7 and the opening 31b in the milker pail is slipped over the polishing member 57, arm 56 and gear housing 52. The milker pail is positioned within the lower grasping member 61 so that the side of the pail rests against the hollowed out section 61a and the bottom of the pail is pressed against the rear of this hollowed out section. The upper grasping member 62 is then rotated about its hinge 63 to the position shown in Fig. 7 and the lock 64 is closed. Power is applied to the apparatus through the belt pulley so as to cause rotation of the driving shaft 49 and the driven shaft 55. This causes rotation of the arm 56 and thus applies a polishing action to the inner surface of the pail adjacent the weld 31a. In order to aid in the polishing operation it is preferred that a polishing oil be introduced into the interior of the pair before the power is turned on.

During the polishing operation the polishing member 57 is forced outwardly against the pail by a combination of centrifugal force and the force of the springs 59. During the polishing operation the lever 69 is reciprocated back and forth around its fulcrum 69a thereby causing the extended collars 65 to slide on the rods 66 and set up reciprocation of the milker pail. Such reciprocation causes the polished area to blend smoothly with the remainder of the pail. After the weld has received a sufficient polishing action, the power is shut off and the upper grasping member 62 is unlatched from the lower grasping member 61. The upper grasping member is then moved to open position and the milker pail removed from the apparatus.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. The method of working the inner circumfer-

ential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped working tool that comprises a rotatable driven shaft within the pail arranged at substantially right angles to the plane of the seam and substantially concentric to the seam, driving means operatively connected thereto and including a portion extending through said opening in the pail and to the driven shaft, and collapsible working means mounted on the driven shaft for rotation therewith and normally bearing against said inner surface for operation thereagainst during rotation of the driven shaft, the collapsible working means and the driven shaft and adjacent driving means having diameters, widths and lengths such that when the working means is in a collapsed state the pail may be readily slipped thereover; clamping the pail in said position; and rotating the driven shaft and associated working means with the working means in contact with the inner surface of the pail at the seam.

2. The method of grinding the inner circumferential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped grinding tool that comprises a rotatable driven shaft within the pail arranged at substantially right angles to the plane of the seam and substantially concentric to the seam, driving means operatively connected thereto and including a portion extending through said opening in the pail and to the driven shaft, and collapsible grinding means mounted on the driven shaft for rotation therewith and normally bearing against said inner surface for operation thereagainst during rotation of the driven shaft, the collapsible grinding means and the driven shaft and adjacent driving means having diameters, widths and lengths such that when the grinding means is in a collapsed state the pail may be readily slipped thereover; clamping the pail in said position with apparatus including heat-conducting and heat-dissipating means bearing against the outer circumferential surface of the pail in the region of the seam; and rotating the driven shaft and associated grinding means with the grinding means in contact with the inner surface of the pail at the seam.

3. The method of polishing the inner circumferential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped polishing tool that comprises a rotatable driven shaft within the pail arranged at substantially right angles to the plane of the seam and substantially concentric to the seam, driving means operatively connected thereto and including a portion extending through said opening in the pail and to the driven shaft, and collapsible polishing means mounted on the driven shaft for rotation therewith and normally bearing against said inner

surface for operation thereagainst during rotation of the driven shaft, the collapsible polishing means and the driven shaft and adjacent driving means having diameters, widths and lengths such that when the polishing means is in a collapsed state the pail may be readily slipped thereover; clamping the pail in said position; and rotating the driven shaft and associated polishing means while reciprocating the pail laterally of the plane of rotation of the polishing means with the polishing means in contact with the inner surface of the pail at the seam.

4. The method of working the inner circumferential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped working tool that comprises a rotatable driven shaft within the pail arranged at substantially right angles to the plane of the seam and substantially concentric to the seam, a rotatable driving shaft substantially parallel to the driven shaft and extending through said pail opening into the pail, mounting means within the pail extending from the driving shaft to the driven shaft and upon which the driven shaft is rotatably mounted, driving means carried by said mounting means and interconnecting the driving and driven shafts, and collapsible working means mounted on the driven shaft for rotation therewith and normally bearing against said inner surface for operation thereagainst during rotation of the driven shaft, the collapsible working means, driven shaft, inner end of the driving shaft, mounting means, driving means, working means, and associated parts having diameters, widths and lengths such that when the working means is in a collapsed state the pail may be readily slipped thereover; clamping the pail in said position; and rotating the driving shaft and thus the driving means, driven shaft and associated working means with the working means in contact with the inner surface of the pail at the seam.

5. The method of grinding the inner circumferential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped grinding tool that comprises a rotatable driven shaft within the pail arranged at substantially right angles to the plane of the seam and substantially concentric to the seam, a rotatable driving shaft substantially parallel to the driven shaft and extending through said pail opening into the pail, mounting means within the pail extending from the driving shaft to the driven shaft and upon which the driven shaft is rotatably mounted, driving means carried by said mounting means and interconnecting the driving and driven shafts, and collapsible grinding means mounted on the driven shaft for rotation therewith and normally bearing against said inner surface for operation thereagainst during rotation of the driven shaft, the collapsible grinding means, driven shaft, inner end of the driving shaft, mounting means, driving means, grinding means, and associated parts having diameters, widths and lengths such that when the grinding means

is in a collapsed state the pail may be readily slipped thereover; clamping the pail in said position with apparatus including heat-conducting and heat-dissipating means bearing against the outer circumferential surface of the pail in the region of the seam; and rotating the driven shaft and associated grinding means with the grinding means in contact with the inner surface of the pail at the seam.

6. The method of polishing the inner circumferential surface of a milker pail having a substantially circular side wall containing a substantially circular butt-welded seam and having a small opening of a diameter less than one-half the diameter of the pail in the top wall of the pail and offset from the center thereof, comprising: positioning the pail on an elbow-shaped polishing tool that comprises a rotatable driven shaft within the pail arranged at substantially right angles to the plane of the seam and substantially concentric to the seam, a rotatable driving shaft substantially parallel to the driven shaft and extending through said pail opening into the pail, mounting means within the pail extending from the driving shaft to the driven shaft and upon which the driven shaft is rotatably mounted, driving means carried by said mounting means and interconnecting the driving and driven shafts, and collapsible polishing means mounted on the driven shaft for rotation therewith and normally bearing against said inner surface for operation thereagainst during rotation of the driven shaft, the collapsible polishing means, driven shaft, inner end of the driving shaft, mounting means, driving means, polishing means, and associated parts having diameters, widths and lengths such that when the polishing means is in a collapsed state the pail may be readily slipped thereover; clamping the pail in said position; and rotating the driving shaft and thus the driving means, driven shaft and associated polishing means while reciprocating the pail laterally of the plane of rotation of the polishing means with the polishing means in contact with the inner surface of the pail at the seam.

7. The method of working the inner circumferential surface of a milker pail having a substantially circular side wall containing a substantially circular butt-welded seam and having a small opening of a diameter less than one-half

the diameter of the pail in the top wall of the pail and offset from the center thereof, comprising: positioning the pail on an elbow-shaped working tool that comprises a rotatable driven shaft within the pail arranged at substantially right angles to the plane of the seam and substantially concentric to the seam, a rotatable driving shaft substantially parallel to the driven shaft and extending through said pail opening into the pail, first mounting means within the pail extending from the driving shaft to the driven shaft and upon which the driven shaft is rotatably mounted as its sole support, driving means carried by said mounting means and interconnecting the driving and driven shafts, a relatively narrow second mounting means arranged closely adjacent to the driving shaft and serving as a support therefor and rigidly connected to the first mounting means, and collapsible working means mounted on the driven shaft for rotation therewith and normally bearing against said inner surface for operation thereagainst during rotation of the driven shaft, the collapsible working means, driven shaft, inner end of the driving shaft, mounting means, driving means, working means, and associated parts having diameters, widths and lengths such that when the working means is in a collapsed state the pail may be readily slipped thereover; clamping the pail in said position; and rotating the driving shaft and thus the driving means, driven shaft and associated working means with the working means in contact with the inner surface of the pail at the seam.

JACOB J. STAMPEN.
